SUCKER ROD GUIDE

J. W. Gillespie, Henderson, Tex.

Application August 24, 1944, Serial No. 551,039

6 Claims. (Cl. 308—4)

1

The invention relates to a sucker rod guide which is particularly adapted to center a string of reciprocating sucker rods used in manipulating a reciprocating pump in a well bore.

It is well understood that wells are not as a general rule straight or vertical, but may be inclined or spiral so that the string of flexible rods extending into the well is inclined to rub against the tubing or pipe through which the oil is being pumped. In order to guide the rods and avoid wear on the tubing suitable guides are connected to the metal rods in order to center the rods in the pipe or tubing while permitting the flow of oil past the guide.

It is one of the objects of the present invention to provide a sucker rod guide which is made up of an integral block of wood or suitable material which is so grooved and slotted that it can be tilted laterally of the rod, applied thereto and then turned to a position concentric with the rod so as to lock the guide against release so long as it is confined in substantial alignment with the rod.

Another object of the invention is to provide a non-metallic sucker rod guide having a cross slot adjacent its middle which joins two diametrically opposite slots, one of which is at each end of the guide.

Another object of the invention is to provide a sucker rod guide having a longitudinal slot extending inwardly from each end thereof where the slots are on opposite sides of the center and where the slots are joined by a transverse recess or groove adjacent the middle of the guide.

Another object of the invention is to provide a sucker rod guide which is arranged to be fitted laterally against the rod in an inclined position and then tilted into alignment with the rod to automatically lock itself against removal.

Still another object of the invention is to provide an integral one-piece sucker rod guide which requires no bolts, fittings or attachments and which automatically locks itself to the rod when placed in operating position.

Other and further objects of the invention will be readily apparent when the following description is considered in connection with the accompanying drawings wherein:

Fig. 1 is a side elevation of one side of a sucker rod to which the guide has been applied and illustrates the locking portions to hold the guide in place.

Fig. 2 is a side elevation of the other side of the sucker rod guide.

Fig. 3 is a side elevation taken at 90° with respect to each of the other two views.

2

Figs. 4 and 5 are sectional views taken on the lines 4—4 and 5—5 of Figs. 1 and 3 respectively.

In Fig. 1 a sucker rod is illustrated at 2 and is usually of steel and may be 30 to 40 feet in length.

6 The rod shown in approximately actual size.

This rod has a squared shank or section 3 thereon by which a wrench or other tool may be applied in order to turn the rod and cause the threaded shank 4 to engage with the socket of the next adjacent rod. The flange 5 abuts against the end of the socket to form a tight connection.

The squared section 3 is defined by the enlarged or belled portion 7.

The sucker rod guide 10 is shown as having 15 been applied to the rod so that the surface 11 thereof will form a guiding surface and slide on the inner surface of the tubing in which the rod is to reciprocate.

Heretofore various types of guides have been 20 provided which were generally constructed of one or more parts which had to be fixed together about the rod to hold them in place. Considerable difficulty has been encountered with screws and bolts, clamps and other fittings for holding 25 the parts of the guide together because due to the shock and vibration and the passing stream of oil the guides soon became loosened and very often the parts were dropped into the well.

The present guide contemplates a single body 30 member having no attachments, fittings, screws or bolts which can come loose or fall off, but where the guide can be automatically locked to the rod without any other attachments to either secure it or to thereafter hold it in place.

35 The drawings show that the guide 10 is made up of a cylindrical body 14 which may be of a suitable material such as hard wood and which has been turned in the form of a cylinder with the rounded ends 15 so that the periphery is 40 merged with the flat end 16.

While it is stated that the guide may be made of hard wood, it seems obvious that it may be made of any suitable material or that it may be molded or cast of suitable materials or metals 45 such as brass, cast iron, or of non-metallic material. Hard wood or wood treated to harden it as with uric acid may be used.

The guide is of peculiar configuration in order 50 to permit its attachment to the rod without the use of other fittings.

The side view in Fig. 3 illustrates a transverse inclined groove 20 which is of a width somewhat greater than the diameter of the rod 2 and it will be noted that this groove is inclined at about 30° 55 with the horizontal. This groove as seen in Figs. 1 and 2 extends radially inward to the central

recess or opening 21 which extends through the center of the guide and which is of a size to receive the rod 2 as best seen in Fig. 2.

In order to position the sucker rod in this central opening the body 14 has been slotted as at 22 on one end and 23 on the other end. The lower end 22 as seen in Fig. 2 has the annular portion 14 of the body cut away for a small arc of its circumference so that such slot 22 forms an entrance for the rod 2 as best seen in Fig. 5. The slot 22 may have the straight walls 24 and a beveled or flared entry 25.

The upper end 21 of the guide body 14 has a somewhat similar slot or opening 23 formed therein where the central opening 21 has been extended out through the side of the body. The only difference between this upper opening 23 and the lower opening 22 is that the upper opening must be of a configuration to receive the squared portion 3 and the flared portion 7 which are a part of the rod.

This structure is best seen in Fig. 1 where the opening 21 is flared at 30 to receive the flared portion 7 and squared at 31 to receive the square portion 3. This slot may be beveled at 34 to permit the ready entry of the parts.

In actual use the guide 10 will be tilted at the same angle as the cross groove 20 with respect to the axis of the sucker rod. It will then be moved laterally against the rod so that the groove 20 passes about the rod. The body is then tilted so as to move it into axial alignment with the rod to assume the positions shown in the drawings. As this tilting movement occurs the rod moves into the grooves 22 and 23 and the fit of the parts is such that the application of a firm pressure will cause the tapered portions 30 and 31 to wedge together at the same time that the squared portions 3 and 31 move together. The flared lip of the tapered portion 17 thus fits into an enlarged circular area 40 inside of the body. It seems obvious that when the body is turned about the slot 20 as the center that the grooves 22 and 23 will move to enclose the portions of the rod. When the guide is thus applied and the rod lowered into the tubing it seems clear that the guide cannot thereafter tilt with respect to the rod anywhere near the required angle or arc to permit the parts 3 and 7 to move out of the complementary recesses in the guide body. If the guide cannot tilt relative to the rod when it is in the tubing, then of course the non-circular and flared portions of the rod and the guide hold the guide against longitudinal sliding movement to such extent that it will reciprocate with the rods.

While the invention has been particularly described as being a guide made of wood, it is to be understood that it can be made of metal or non-metallic material and that it may be of different sizes and lengths depending upon the relative sizes of the guides and the tubing.

Broadly the invention contemplates a self-aligning, self-locking sucker rod guide which is held in position concentric with the axis of the tube of the sucker rod.

What is claimed is:

1. A sucker rod guide comprising an integral body of material, a slot along the axis of the body, said slot being of an inverted bell shape to have a portion open out through the body for one half of the block, another portion open out through an opposite side for the other half of the body and having an inclined portion joining the two first portions so that the body may be

tilted and moved laterally to pass said inclined slot portion over the rod and the body then turned to pass the first two portions over the rod to lock the guide to the rod so long as the guide is retained in a pipe, one of said slots being shaped to interfit a portion of the rod to hold the guide fixed on the rod.

2. A sucker rod guide comprising an integral body of material, a slot along the axis of the body, said slot being of an inverted bell shape to have a portion open out through the body for one half of the block, another portion open out through an opposite side for the other half of the body and having an inclined portion joining the two first portions so that the body may be tilted and moved laterally to pass said inclined slot portion over the rod and the body then turned to pass the first two portions over the rod to lock the guide to the rod so long as the guide is retained in a pipe, one of said first slot portions being contoured to receive the squared area of the sucker rod so as to retain the guide against longitudinal movement on the rod.

3. A self retaining and locking sucker rod guide for rods having a squared area and comprising a cylindrical body, a circular opening through said body having an inverted bell-shaped portion to fit a complementary portion on the rod, a slot extending laterally into said opening, said slot being cut to extend in one radius for one half of the body, in an opposite radius for the other half of the body and having an inclined portion joining such halves.

4. A self retaining and locking sucker rod guide for rods comprising a cylindrical body, a circular opening through said body, a slot extending laterally into said opening, said slot being cut to extend in one radius for one half the body, in an opposite radius for the other half of the body and having an inclined portion joining such halves, an area of said opening being of an inverted bell shape to fit a complementary area of the rod.

5. A sucker rod guide including circular body, said body having a central rod receiving opening including a slot radially out through the block in opposite directions in the opposite ends of the block, a lateral slot portion merging said first slots adjacent the middle of the body so that the body may be tilted, applied to the rod and then turned to a position concentric with the rod, said first slot having an inverted bell shaped area therein contoured to receive and retain a complementary portion of the sucker rod.

6. A sucker rod guide including circular body, said body having a central rod receiving opening including a slot radially out through the block in opposite directions in the opposite ends of the block and a lateral slot portion merging said first slots adjacent the middle of the body so that the body may be tilted, applied to the rod and then turned to a position concentric with the rod, one of said slots and a portion of said opening being formed to receive and retain an inverted bell shaped area on the rod.
